CHARLES F. THOLIN, OF ROCKFORD, ILLINOIS, ASSIGNOR TO THE SKANDIA FURNITURE COMPANY OF ROCKFORD, ILLINOIS, OF ROCKFORD, ILLINOIS, A CORPORATION OF ILLINOIS.

AUTOMATIC DESK-FALL SUPPORT.

Application filed March 20, 1925. Serial No. 16,877.

This invention relates in general to furniture and has more particular reference to means for supporting the hinged fall or lid of a writing desk or cabinet in the lowered position.

Heretofore means have been provided for this purpose characterized by a sliding member or fall support mounted on the case at each end of the fall and connected thereto so that upon swinging the fall to the lowered position the slides will be moved forward to a fall-supporting position and upon swinging the fall back to its raised or closed position the slides will be retracted into the case. These prior constructions are however, unsatisfactory in that the means employed for operating the slides are comparatively complicated and costly considering their function; and furthermore, they invariably presented an objectionable appearance because of their many parts and rather bulky construction.

The primary purpose of the present invention is therefore, to provide an improved construction of this kind with a view to obviating objections to prior devices for this purpose. In other words, I have aimed to provide an exceptionally simple and practical automatic fall support comprising a minimum number of parts so constructed that they may be produced at a comparatively low cost and which when embodied in a desk or other cabinet employing a hinged fall or lid will occupy but very little space and be practically concealed and out of the way.

Other objects and attendant advantages will be appreciated by those skilled in this art as the invention becomes better understood by reference to the following description when considered in connection with the accompanying drawings, in which—

Figure 1, is a perspective view of the upper portion of a writing desk equipped with an automatic fall support embodying my invention;

Fig. 2, is a vertical section taken substantially on the line 2—2 of Fig. 1; and

Figs. 3, 4 and 5 are sections taken on the lines 3—3, 4—4 and 5—5 respectively of Fig. 2.

My invention in its preferred embodiment is illustrated herein as applied to a writing desk. It should be understood however,

that it is applicable to any cabinet or piece of furniture having a hinged fall or lid similar to the fall of a writing desk which requires some form of support for holding it in the open or horizontal position in which it is suspended from its hinged end. The writing desk shown comprises a suitable case the principal parts of which to be considered herein are the sides or ends 6 and 7, a fall bottom 8 fitting at its ends in grooves 9 in the sides as shown clearly in Fig. 4, and a fall 11 suitably hinged at 12 to the front edge of the fall bottom 8. In this instance the case below the fall bottom 8 provides a cabinet having a series of drawers as shown in Fig. 1.

It is desired that the fall-supporting means, preferably in the form of slides, and the means for automatically operating the slides shall occupy minimum space and be so located as to be practically out of sight both when the fall is in the raised and lowered position. It is also desired that the construction shall comprise but a minimum number of parts so constructed that they may be produced and installed at a comparatively low cost. It is further desired, but not essential, that the construction shall be such as to permit the use of a continuous hinge for the fall support, the total cost of which hinge together with the slide operating means is less than that of prior constructions which invariably did not appear as neat and attractive as the present construction.

With these objectives in view I have provided the following construction: Beneath each end of the fall bottom 8 I mount a fall-supporting member or slide 13 with its top edge 14 contiguous to the underside of said fall bottom and with its outer side 15 contiguous to the inner side of the case and 6 or 7. Each fall-supporting member is suitably supported to slide forwardly and backwardly in a horizontal plane, that is, forwardly from the retracted position shown in full lines in Fig. 2 to the extended, fall-supporting position shown in dotted lines, and rearwardly to the retracted position. In this instance each end of the cabinet has a surface 16 on which the fall-supporting member slides at its front end and is equipped at its inner side with a roller 17 and a retaining flange 18, or equivalent

means, for guiding and retaining the rear end of said member. Each end of the fall bottom 8 is cut away to provide an elongated slot 19 the ends of which are defined by walls 21 and 22 and is further cut away or slotted on its top surface to provide a shallow groove 23 in alignment with and connecting the slot 19 with the front edge of said board. In the rabbeted edge 24 of each end of the fall is pivotally connected at 25 one end of a link 27, the opposite end of which is bent at right angles providing an offset end portion 27 terminating in a laterally, inwardly turned end 28. As shown in Fig. 3 the link 15 26 (duplicated at the opposite end of the case) is disposed in the plane of the slot or opening 19 so that its offset portion 27 may extend down through said opening as shown in Figs. 2 and 5. The lower end of said 20 offset portion 27 enters a cutaway 29 in the outer side of the slide and the inwardly turned end 28 of the link enters a hole in the slide as shown in Fig. 5 and provides a pivotal connection thereto. In the preferred 25 embodiment of my invention the link 26 is in the form of a single piece of wire one end of which is flattened for the connection 25 and the opposite end of which is bent to the shape described to provide a simple and effective connection to the slide without the 30 use of extraneous fastening means. To this end it will be noted that the slide-connected end of the link is confined between the side walls of the slot or opening 19 and thus 35 maintained in operative relation at all times to the slide and fall board. As a result of this construction there is no side twist or strain on the links and their pivotal connections when the fall board is swung back 40 and forth.

From the foregoing it will be manifest that when the fall is swung down to the lowered position shown in dotted lines in Fig. 2 the slides 13 will be automatically drawn forwardly by the links 26 to the fall-supporting position shown in dotted lines. In this 45 position it will be observed that the links 26 occupy a position partly in the rabbeted edge 24 of the fall and partly in the shallow 50 groove 23 in the fall bottom 8, flush with the top of said fall and fall bottom. The con-

necting links are therefore, in an out-of-the-way position and not obstructive to the full use of the writing top. Furthermore, by reason of the construction and arrangement 55 of the connecting links they occupy but very little space and are practically out of sight and do not mar the symmetry and design of the desk or cabinet. It will be manifest that when the fall is raised to the upper closed position the connecting links 26 will by such action retract the slides to the position shown in full lines in Fig. 2.

By reason of my invention, an automatic fall support having the desirable characteristics above-mentioned may be produced and installed at a lower cost than any prior construction of which I am aware. The construction is moreover amply strong and durable to perform the desired function, and is 60 65 thoroughly practical.

It is believed that the foregoing conveys a clear understanding of the objects prefaced above and while I have illustrated but a single working embodiment it should be understood that changes might be made in details of construction without departing from the spirit and scope of the invention as expressed in the appended claim, in which—

I claim:

A device of the character described comprising a link arranged to be pivotally connected at one end to a desk fall and at its other end to a fall-supporting slide to operate the latter, the said link being made 85 of a single piece of wire formed at one end to make pivotal connection with the fall and having the other end bent downwardly for passage through a slot in the fall bottom to the slide and having the extremity bent 90 laterally for entry in a bearing hole provided in the slide, the said wire being of medium size so as to operate easily through a narrow slot in the fall bottom as well as permit of a certain amount of rebending of the bent 95 end to conform the link to the location of the bearing hole, and said wire being preferably round so that the bent extremity provides a good journal part without special conforming thereof.

CHARLES F. THOLIN.
